UNITED STATES PATENT OFFICE.

MENDEL HOWARD, OF NEW YORK, N. Y.

BROOCH-PIN.

SPECIFICATION forming part of Letters Patent No. 402,672, dated May 7, 1889.

Application filed November 22, 1888. Serial No. 291,709. (No model.)

To all whom it may concern:

Be it known that I, MENDEL HOWARD, a citizen of the United States, and a resident of the city of New York, county of New York, 5 and State of New York, have invented a new and useful Improvement in Brooch-Pins, of which the following is a specification.

The object of the invention is to produce an improved brooch-pin which can be easily 10 attached to and detached from the garments of the wearer.

The nature of the invention consists in the details of combination and construction, substantially as illustrated in the accompanying 15 drawings, hereinafter described, and subsequently pointed out in the claims.

Figure 1 is a sectional view of a brooch embodying my invention. Figs. 2, 3, 4, 5, and 6 all illustrate different modifications of my invention, more fully hereinafter described. 20 Figs. 7, 8, 9, and 10 are detail views of parts of the mechanism, more fully hereinafter described.

In Fig. 1, A designates a tube, which is 25 mounted upon the back of the brooch. n b' n designate a needle bent so that the two prongs n and n will be nearly parallel to each other.

At the end of the tube A is an ear, B. This 30 ear is pierced with two holes, g and l. Through the hole l passes one of the prongs n, and extends to within the tube A. The end of this prong within the tube terminates in a piston-like plug, C, which, while it is adapted to the 35 interior of said tube, is free to be slipped therein. A stationary needle, n', is fastened to said tube and extends toward the middle of and parallel to said tube. To meet this, one of the prongs n passes through the hole 40 g of the ear B, and, extending parallel to said tube, reaches beyond the point of n'; or this needle n' may be fastened near the middle of the tube A and pointed in the same direction as the needle n; or the needle n' may be replaced by a clip, F, which may be adapted to 45 engage the point of the needle n, as illustrated in Fig. 3. For this clip may be substituted a loop, as illustrated by F' of Fig. 4.

B' of Fig. 7 illustrates the ear through which 50 the needle n passes. g designates the hole through which the needle passes, and f the base-pieces supporting said ear.

In all the figures, G represents the front piece of the brooch.

Fig. 5 illustrates a modification of my invention, in which are two parallel tubes, R and R', an ear, B, at either end of these tubes, and two needles, n² and n³, having finger-knobs b' sliding in said tubes R R', passing through the holes g and l of the ears B, and overlapping each other, as illustrated.

Fig. 6 illustrates another modification of my invention. In this case the tube A is dispensed with, and the part m o of the needle L, Fig. 9, slides on the back of the mounting-plate. For that purpose the end of the needle may be flattened, as illustrated by m o of Fig. 9, or the end thereof may be bent into a loop, as illustrated in Fig. 10, and designated by o'.

Fig. 8 illustrates a form of the mounting-plate, which, in order to accommodate the end m of the needle, may be struck with the groove t running from side to side in said plate, and in which, for greater steadiness, 75 the said part of said needle moves, the whole to be substantially as illustrated in the drawings. To use this invention, the operator in the case of Figs. 1 and 2 draws out the sliding needle n, and, having hooked the stationary 80 pin n' into the garment, so that the brooch will be held in proper position, secures it there by pushing in the needle n, which, running into the clothes, firmly holds the brooch to the garment of the wearer. This same way is applied to the use of the form of the brooch 85 illustrated by Fig. 6.

In the case of Figs. 3 and 4 the needle is drawn out and the brooch held in proper position, so that when the needle is pressed in again 90 it will pass through a part of the garment and into the clip F or the loop F', and so retain the brooch in proper position. In the case of Fig. 5 both needles are drawn out, the brooch placed in proper position, and both needles 95 pushed in to secure it there. To release the brooch, the sliding needles are drawn out, and then the brooch may be easily removed from the garment.

What I claim as my invention, and desire 100 to secure by Letters Patent, is—

1. The combination, with the mounting-plate of a brooch, a guide in and upon said mounting-plate, and an ear upon said mount-

ing-plate at the end of said guide, of a pronged needle of the form specified, one prong of which, passing through said ear, slides in said guide, and the other prong of which, also passing through said ear into a garment, partly holds said brooch in position, and an auxiliary stationary needle attached to said mounting-plate and arranged to assist said sliding needle in securing said brooch to a garment, 10 all substantially as and for the purpose set forth.

2. The combination, with the mounting-plate of a brooch, a guide in and upon said mounting-plate, and an ear upon said mounting-plate at the end of said guide, of a pronged needle of the form described, one prong of which, passing through said ear, slides in said guide, and an enlargement upon the end of said prong adapted to said guide and moving 15 therein, the other prong of said needle also passing through said ear, a part of the garment to which said brooch is to be fastened, and into a supporting-piece upon said mounting-plate, and said supporting-piece, formed 20

and attached as specified, all substantially as 25 and for the purpose set forth.

3. The combination, with the mounting-plate of a brooch, tubes upon said mounting-plate extending across and parallel thereto and parallel to each other, and ears formed 30 upon said mounting-plate at either end of said tubes, of two pronged needles, substantially as specified, one prong of each of said needles passing through one of said ears and sliding in one of said tubes, and the other 35 prong of each of said needles passing through one of said ears and extending without said tubes to and beyond the middle thereof nearly parallel thereto, so as to overlap each other in the garment to which said brooch is to be attached, all substantially as and for the purpose set forth.

In witness whereof I hereunto set my hand in presence of two witnesses.

MENDEL HOWARD.
